[57] CLAIM

The ornamental design for a fly trap, as shown and described.

DESCRIPTION

FIG. 1 is a front, top and right end perspective view of a fly trap showing our new design;

FIG. 2 is a top plan view thereof;

FIG. 3 is a rear elevational view thereof, the front elevational view being a mirror image;

FIG. 4 is a bottom plan view thereof;

FIG. 5 is a right end elevational view thereof; and,

FIG. 6 is a left end elevational view thereof.

The screen covering is continuous throughout.

The broken line showing in FIGS. 1, 2 and 3 represents staples used in the assembly of the design.
